UNITED STATES PATENT OFFICE.

ALONZO FROST, OF TROY, NEW YORK, ASSIGNOR OF ONE-HALF TO FRANK FROST, OF SCHENECTADY, NEW YORK.

THREAD-GUARD.

1,095,841.

Specification of Letters Patent.

Patented May 5, 1914.

Application filed October 30, 1912. Serial No. 728,661.

To all whom it may concern:

Be it known that I, ALONZO FROST, citizen of the United States, residing at Troy, in the county of Rensselaer and State of New York, have invented certain new and useful Improvements in Thread-Guards; and I do hereby declare the following to be a full, clear, and exact description of the invention, such as will enable others skilled in the art 10 to which it appertains to make and use the same.

This invention relates to improvements in take-ups for a sewing machine, and more especially to thread guards for the take-up. 15 An object of the invention is to provide a cover for the take-up which will not only prevent accumulation of dust in the take-up mechanisms, but will also prevent the entanglement of the thread with any part of 20 the mechanism when the thread breaks.

A further object of the invention is to provide the cover with additional means for preventing a wrapping of broken thread around the take-up cam disks or the shaft 25 driving the same.

With these and other objects in view the invention comprises certain novel constructions, combinations, and arrangements of parts as will be hereinafter more fully described and claimed.

In the drawings: Figure 1 represents the take-up of the sewing machine with my invention applied thereto shown in perspective. Fig. 2 is a top plan view of the cover 35 constituting my invention. Fig. 3 is a vertical section along the shaft.

Heretofore, it has been found that when the thread broke at the needle or needles of a sewing machine, especially that type 40 known as the Union Special, the revolving parts of the take-up catch the thread and wrap it around the driving shaft or cam disks, which results in not only waste of the thread, but also in unthreading the 45 needles, so that before the operator can resume work it is necessary to free the take-up of the entangled thread, rethread the needles, rip out the unfinished seam, and resew the entire seam, all of which is at the 50 expense of the operator's time and patience.

Various attempts have been made to prevent this accumulation of thread in the take-up, but none of them has proved successful. My invention, which has proved 55 successful in practice, may be said, gener-

ally, to comprise a protecting plate, which, acting as a dust guard, also prevents the thread from entering the mechanism of the take-up, a tongue extending from the plate into the groove of the take-up cam disks, 60 and an adjustable spring secured to the cover and being in constant engagement with the said cam disks. No additional means is required for holding the plate in position on the sewing machine. 65

In the accompanying drawings where I have shown my invention as applied to the take-up of the aforementioned type of sewing machine, 1 represents a housing; 2, a shaft mounted in the housing; 3, cam disks 70 carried by the shaft; 4, a guide supporting block mounted in the housing; 5, thread guides held to the said block by means of springs 6; 7, nipper springs through which the thread passes; 8, a throw-off arm; and 75 9, a retaining arm.

The construction thus far described is old in the art, and I do not claim any of it as my invention.

My invention comprises a plate 10 of such 80 outline as to enable the same to be fitted to the housing 1, said plate being provided with a substantially rectangular opening 11 which enlarges into an opening 12 formed in the plate near the rear of the take-up. 85 Extending from the enlarged opening 12 is a second substantially rectangular opening 13 parallel to opening 11, and having extending into one end thereof a spring 14. This spring 14 may be formed integral with 90 plate 10 or secured to such plate, as may be desired. The openings 11 and 13 define a projecting strip 15 which with the plate 10 forms a restricted cut 16 in the rear part 95 of opening 13. As shown at 17, the plate 10 is cut so as to fit around the journal of the shaft 2, this construction giving a substantially dust proof fit between the plate 10 and the rest of the sewing machine. Secured as at 18 is a wire spring 19 having a 100 suitable coil formed therein and having formed at the other end a loop 20 which is adapted to receive a screw 21. The spring 19 is designed normally to press against one of the cam disks, and the pressure between 105 the spring and cam disks may be regulated by the coil. Tapped in one side of the guide supporting block 4 is a hole 22 adapted to receive the screw 21, whereby the spring 19 is securely held to the said supporting block. 110

The plate 10 is provided with an indentation 23, which is in alinement with corresponding recesses in the housing 1, the thread being adapted to pass through said recess and indentation. When it is desired to adjust the lateral position of the spring 19, it is merely necessary to turn the cams so that the coil can be bent laterally away from the cam disk with the fingers, this lateral bending or stretching of the wire of the spring being accompanied by a corresponding reduction in the size of the coil.

As shown in Fig. 3, the underside of the projection 15 and the underside of the plate 1 to the right of opening 13 are provided with strips of felt 24 said strips of felt being adapted to extend a short distance into opening 13 and engage the outer sides of the cam disks. If desired, these strips of felt 20 may be made of such thickness as will fill the space between the plate and shaft.

In applying the plate 10 to the take-up device it is merely necessary to raise the guide 5 to an upright position, slip the plate 25 on to the take-up so that the guide passes through the opening 12, and the cut-away portion 17 is in close contact with the journal box of shaft 2, lower the guide to the position indicated in Fig. 1, and secure loop 20 of the spring 19 to the guide block by means of screw 21. From this it will be seen that the spring 6, acting through the thread guide 5, serves to hold the plate 10 in position, and no other means is employed for securing the plate.

In the operation of this device, it is to be understood that the shaft is revolving at a high rate of speed, and that the thread is normally under tension. If for any reason 40 the thread should break at the needles, and the take-up is not provided with my invention, the loose end of the thread would be thrown upon the shaft 2 by the take-up disk and become so entangled with said shaft 45 that in a very short time considerable thread would be wrapped around the shaft.

Experience has shown that in a great number of instances the thread wraps around that part of the shaft between the cam disks 50 and the machine proper, insomuch as the loose end of the thread is nearer this part of the shaft. By placing my plate upon the take-up, it will be seen that when the thread breaks, the cam disks throw the same upon 55 the spring 19 which operates to throw the thread to the rear of the take-up, and thus avoid entanglement with the revolving shaft. However, if only the spring 19 were provided, the free end of the broken thread 60 might become entangled with the shaft, hence the necessity of providing a plate which will make it impossible for the thread to come in contact with the revolving shaft.

In an endeavor to line the bottom part of 65 the plate lying adjacent the two cam disks

with felt, it has been found that the felt secured near the rear of the plate is torn off by the cam disks, insomuch as their direction of rotation at that part of the plate is downward. One of the principal uses of the 70 spring 19 is to supplant this felt, this spring 19 being formed on one side of the cam disk and extending over that portion of the disk where it has been impracticable to secure felt. As the cam rotates, the flat portions 75 of the cam, such as are at present in use and a sample of which is illustrated in the drawings, will carry the thread into the opening in the plate, through which the disk passes, unless the spring 19 is provided. If the 80 spring be not present, the thread will be carried through the opening and will either wrap around the shaft or be cut by the side of the plate. It is not necessary that the 85 spring 19 actually engage the disk, but it is desirable to have the distance between the 90 spring and disk considerably less than the thickness of the thread which is being used. While a spring has been shown, yet this is not the only means which may be associated 95 with the plate for casting off the thread, but is given as one example. The plate 10, together with the felt lined opening 13, and the projecting tongue 14 form an effective 100 means for keeping the thread from the shaft.

In order that operator may be assisted in removing the plate from the machine, an opening is struck from the plate at a point just under one end of the thread guide, so that the thumb or finger may be slipped 105 easily under the guide to raise the plate when it is necessary to thread the take-up mechanism. Of course, it is obvious that the opening could be replaced by a recess formed in the plate, in which event the interior of the take-up is kept dust proof.

What I claim is:

1. A thread guard for takeups provided with cam disks comprising a plate surrounding the cam disks, and a spring secured to the plate and adapted to bear against the 110 cam disks.

2. In a thread guard for take-ups, provided with a plurality of cam disks, a plate surrounding the cam disks, and a tongue extending from the plate and between adjacent disks.

3. In a thread guard for take-ups provided with a cam disk, a guard plate having an opening therein, the under part of the 120 plate being lined with felt around the opening, the cam disk being mounted to rotate through the opening and adapted to engage the felt lining.

4. In a thread guard for take ups provided with cam disks, a plate having an opening therein adapted to receive the cam disks, the edges of the opening being lined with felt, a tongue extending from the plate and between adjacent cam disks, and a 125 130

spring secured to the plate and adapted to bear against the side of one of the cam disks.

5. In a thread guard for takeups provided with cam disks, a resilient member adapted to cast off the thread as the disks rotate, one end of said member being fixed with respect to the takeup mechanism, and means for supporting the other end of said resilient member.
- 10 6. In a thread guard for take-ups provided with cam disks mounted upon a shaft,

a plate surrounding the cam disks and located between the thread and the shaft, and means extending from the plate adapted to cast off the thread as the disks rotate. 15

In testimony whereof I affix my signature in presence of two witnesses.

ALONZO FROST.
